UNITED STATES PATENT OFFICE.

BRADFORD C. EDMANDS, OF NEWTON, MASSACHUSETTS, ASSIGNOR TO AMERICAN PIANO COMPANY, OF NEW YORK, N. Y., A CORPORATION OF NEW JERSEY.

GRAND-PIANO CONSTRUCTION.

1,401,115.

Specification of Letters Patent. Patented Dec. 20, 1921.

Application filed October 21, 1920. Serial No. 418,530.

To all whom it may concern:

Be it known that I, BRADFORD C. EDMANDS, a citizen of the United States, and a resident of Newton, in the county of Middlesex and 5 State of Massachusetts, have invented an Improvement in Grand-Piano Construction, of which the following is a specification.

The present invention relates to grand pianos and has for an object to provide an 10 improved grand piano construction and an improved method of assembling grand pianos.

For many years grand pianos have been constructed by a method of manufacture 15 which has involved fitting and securing the skeleton frame and case rim together and subsequently fitting the sounding-board and musical instrumentalities into place within the rim. This method involves carefully fitting 20 the sounding-board into the rim and against the skeleton frame while the rim is in position making the work difficult and expensive. In connection with the fitting of the sounding-board, the skeleton frame must 25 be provided with recesses to receive the ends of the sounding-board ribs. This requires skillful, painstaking workmanship.

It has been proposed, heretofore to assemble the skeleton frame, sounding-board 30 and musical instrumentalities and to make and finish the case rim separately therefrom and thereafter apply it to the previously assembled parts. While this method has resulted in a considerable saving in the 35 manufacture of grand pianos, nevertheless it has certain disadvantages in that the skeleton frame and case rim must still be carefully fitted together. Furthermore, this method ordinarily involves the use of a 40 shop-form for each rim to retain the rim in shape during a relatively long period while it is being operated upon in the process of manufacture and finishing.

The present invention provides a method 45 of manufacture and assembly which permits the manufacture of the skeleton frame, sounding-board and musical instrumentalities as one unit and the manufacture of the case rim as a separate unit and in such form 50 that the two units may be easily assembled without exact trimming and fitting of either part and without requiring labor having a higher degree of skill than that usually found among ordinary cabinet makers. The

skeleton frame is a strong and rigid structure commonly forming a permanent part of the case in pianos of the type to which this invention relates. It holds the case rim in shape and gives the required rigidity to the 55 case.

The quality of a piano depends to a great extent upon the quality and workmanship of the interior parts, that is to say of the skeleton frame, sounding-board, iron frame with the strings and the action. When 60 pianos are manufactured for sale in distant markets considerable expense in transportation can be saved if the frame assembly and action can be manufactured at a central plant where highly skilled piano operatives 65 are available and these parts shipped to a distributing center where the case can be applied and the piano finished by available labor having reasonable skill in cabinet work.

The present invention makes feasible the manufacture and assembling of the more important elements of the piano at one factory and shipment to a distributing center for completion and finishing. This is accomplished by providing an improved construction and method of assembling especially 70 designed to facilitate the application of the rim to the frame assembly without requiring special tools and jigs or a high quality of 75 workmanship.

The invention will be best understood from a specific description of an illustrative structure and a preferred method of assembling such structure.

In carrying out the method of manufacture which will be particularly described the sounding-board, iron frame and strings are preferably assembled on the skeleton frame or rast and then the rim is applied 80 thereto and secured firmly to the skeleton frame. The skeleton frame is preferably made enough smaller than the rim to make allowance for minor irregularities in the shape of either the rim or frame. The rim is 85 stiffened by a reinforcing rib or member extending preferably continuously along the interior thereof and flush with the lower edge. A rigid connection is made between the skeleton frame and rim at spaced points 90 by introducing wedges between the skeleton frame and rim which wedges are glued to both parts and screws are preferably put 95 100 105

through the frame and wedges into the rim to secure the wedges in place and the skeleton frame and rim in suitably spaced relation. The frame preferably is also glued and screwed to the reinforcing rib of the rim. Thereafter the action, pedals, fall board, cover and other parts are assembled with the piano in the usual manner.

Referring more particularly to the accompanying drawing in which is illustrated a grand piano constructed in accordance with the invention,

Fig. 1 is a perspective view of the rim of a grand piano showing a reinforcing rib and skeleton frame support extending along the lower edge and the key-bed secured thereto.

Fig. 2 is a perspective view of a skeleton frame adapted to fit within the rim of Fig. 1.

Fig. 3 is a central sectional view of the skeleton frame with a sounding-board, iron frame and strings assembled thereon.

Fig. 4 is a similar sectional view of the complete piano.

Fig. 5 is a plan view showing only the skeleton frame and rim in assembled relation.

Fig. 6 is a detail sectional view taken on the line 6—6 of Fig. 5.

Fig. 7 is a detail sectional view taken on the line 7—7 of Fig. 5.

Fig. 8 is a perspective view of one of the wedges 20, the taper being shown as exaggerated for the sake of clearness.

In the construction illustrated the rim and skeleton frame are made separately and afterward assembled. The rim member 1 comprises the rim proper 2 (Fig. 1) with the rib 3 extending around the interior thereof preferably adjacent the lower edge, the key-bed 4 and the front bar 4' which are secured to the rim to brace the ends and hold them in proper spaced relation. This rim member may be finished complete and polished before any other parts are assembled therewith. The reinforcing rib 3 performs two functions. It stiffens the rim while it is being operated upon and in the finished piano it provides a support and convenient point of attachment for the skeleton frame when the same is assembled with the rim.

The skeleton frame 5 (Fig. 2) is made separately and is of usual construction except that the outer circumferential frame member in the construction illustrated is narrower than usual by an amount equal to the vertical depth of the skeleton frame supporting rib so that the top is at the usual level with respect to the rim. The central bar 7 and the bottom belly bar 8 of the skeleton frame are also made narrower, at least at their ends where they join the circumferential frame member, so as to fit over

the rib 3 when assembled with the rim as indicated at 10 in Figs. 2 and 3 and at 11 in Fig. 6. The diagonal brace 12 is similarly cut away at its outer end to fit over the supporting rib when assembled.

A leg support 25 is shown suitably secured to the rim and preferably also to the central bar 7 of the skeleton frame.

Assembling is conveniently as follows; the sounding-board 15, iron frame 16 and strings 17 are applied to the skeleton frame and thereafter the skeleton frame with these associated parts is set into the rim. The skeleton frame is glued and screwed to the stiffening rib 3 which now serves as a support for the skeleton frame. The screws, or the stiffening rib with the connecting screws and glue constitute a supporting and securing means for holding the skeleton frame and rim in suitable preferably spaced relation.

The skeleton frame is preferably made smaller than the interior of the rim, as above noted, in order to allow for variation or inaccuracy in the shapes of the skeleton frame and rim to avoid difficult trimming of the skeleton frame at the time of assembling. Preferably additional securing means are provided more securely to hold the skeleton frame and rim in definite spaced relation. As shown, spacing wedges 20 are introduced between the skeleton frame and rim at suitable intervals along their adjacent peripheries and wood-screws 21 are introduced through the skeleton frame and wedges into the rim to secure the frame and rim firmly in fixed relation to each other.

The action of the piano may now be assembled and the piano completed in any suitable or convenient manner.

It is to be understood that the particular method and construction described are merely illustrative of the invention as variations will be obvious to those skilled in the art.

I claim:

1. A grand piano comprising a case rim having an inwardly projecting reinforcing rib, a skeleton frame secured to and supported by said rib, and securing means connecting said skeleton frame and rim to hold the same in fixed relation together with a sounding board and an iron frame.

2. A grand piano comprising a case rim having an inwardly projecting reinforcing rib, a skeleton frame smaller than the interior of the rim, spaced therefrom throughout its perimeter and secured to and supported by said rib together with spacing and securing means between the skeleton frame and rim to hold the same in fixed spaced relation.

3. A grand piano comprising a case rim, a skeleton frame smaller than the interior

of the rim and spaced therefrom throughout its perimeter, securing devices holding the skeleton frame and rim in fixed spaced relation, a sounding board and an iron frame 5 supported by the skeleton frame.

4. A grand piano comprising a case rim, a skeleton frame within and spaced from said rim, securing means holding said skeleton frame and rim in fixed spaced relation, 10 a sounding board and musical instrumentalities supported above said skeleton frame.

5. A grand piano comprising a case rim having an inwardly projecting frame supporting ledge, a skeleton frame supported by 15 said ledge and an iron frame supported by said skeleton frame.

6. A grand piano comprising a case rim having a frame support projecting inwardly at its lower edge, a skeleton frame supported 20 by and secured thereto and an iron frame supported by said skeleton frame.

7. As an article of manufacture, a case rim for a grand piano and a key-bed secured to and connecting the ends of the rim 25 to hold the same in definite spaced relation.

8. As an article of manufacture, a case- 30 rim for a grand piano having a reinforcing rib along its lower edge projecting inwardly and formed to provide a support for the skeleton frame.

9. As an article of manufacture, a case- 35 rim for a grand piano having a reinforcing, stiffening rib projecting inwardly and a key-bed secured to and connecting the ends of the rim.

10. The improvement in the art of constructing grand pianos which comprises constructing and assembling the skeleton frame, sounding-board and musical instrumentalities, constructing and finishing separately 40 the case-rim having a reinforcing rib which affords support for the skeleton frame; assembling the skeleton frame and rim, and

securing the skeleton frame to the reinforcing rib.

11. The improvement in the art of constructing grand pianos which comprises constructing and assembling the skeleton frame, sounding-board and musical instrumentalities, constructing and finishing separately 50 the case-rim having a support for the skeleton frame, setting the skeleton frame into the rim and onto the frame support thereof, and securing the frame and rim together.

12. The improvement in the art of constructing grand pianos which comprises constructing and assembling the skeleton frame, sounding-board and musical instrumentalities, constructing and finishing separately 55 the case-rim, supporting the case-rim and skeleton frame in spaced relation, and securing the skeleton frame to the rim.

13. The improvement in the art of constructing grand pianos which comprises constructing and assembling the skeleton frame, 60 sounding-board and musical instrumentalities, constructing and finishing separately the case-rim with the key bed secured thereto, assembling the skeleton frame and rim, and securing the skeleton frame to the rim. 70

14. The improvement in the art of constructing grand pianos which comprises constructing and assembling the skeleton frame, sounding-board and musical instrumentalities, constructing and finishing separately 75 the case-rim, the skeleton frame being substantially smaller than the rim and spaced therefrom throughout its periphery, inserting spacing-wedges between the skeleton frame and rim, and securing the rim permanently to the skeleton frame. 80

In testimony whereof, I have signed my name to this specification this 18th day of October, 1920.

BRADFORD C. EDMANDS.
